UNITED STATES PATENT OFFICE.

JOHN LOEFFLER, OF EVANSVILLE, INDIANA.

SUSPENDER-BUTTON AND DRAWERS-HOOK.

1,132,595.

Specification of Letters Patent.

Patented Mar. 23, 1915.

Application filed August 6, 1912. Serial No. 713,676.

To all whom it may concern:

Be it known that I, JOHN LOEFFLER, a citizen of the United States, residing at Evansville, in the county of Vanderburg and State of Indiana, have invented new and useful Improvements in Suspender-Buttons and Drawers-Hooks, of which the following is a specification:

This invention relates to the class of buttons, hooks, etc., and more particularly to a combined suspender button and drawers hook.

An object of this invention is to detachably associate the button and hook, to permit the removal of either upon being rendered unsuitable for use, means being provided to preclude possibility of casually displacing the button or hook.

With the foregoing and other objects in view, my invention consists in such details of construction and arrangement of parts as will be hereinafter more particularly described and pointed out in the appended claim.

In describing my invention in detail reference will be had to the accompanying drawings wherein like characters denote like or corresponding parts throughout the several views and in which,

Figure 1 is a front view of a pants button. Fig. 2 is a section of the device with the drawers hook attached. Fig. 3 is a rear view of the button. Fig. 4 is a rear view of the hook attached to the button. Fig. 5 is a rear view of the hook detached, and Fig. 6 is a section of the hook showing the lug and spring members.

In the drawings wherein is illustrated the preferred form of this invention, a button 1 is provided which may be of any desired form, and is provided with a central opening through which a shank 3 passes. One end of the shank is enlarged to provide a head 2, which is snugly engaged with the button, while the opposite end is provided with an elongated enlargement 5 for a purpose more fully hereinafter set forth. In order to illustrate the application of the invention, the shank 3 is shown as engaged

through a member 4, the latter representing 50 a portion of a pair of trousers.

The drawers-hook in the present instance comprises a plate 6 tapering toward one end, said tapered end being reversely folded upon itself to provide a hook 7. An elongated 55 transversely extending slot 8 is formed in the plate 6, and is of a size slightly larger than that of the enlargement 5 of the shank 3, to permit said enlargement to be passed through the slot. A portion of the plate 6, 60 subjacent the opening 8, is struck up at right angles to the plate to provide an abutment 9 for limiting the movement of the enlargement 5, after the latter has been passed through the opening 8. A portion of the 65 plate is partially severed from the plate and bent outwardly therefrom, to provide a spring 10, which is flexed under pressure of the enlargement 5 after the latter has been passed through the opening 8 and turned 70 into engagement with the abutment 9, thereby precluding possibility of casually displacing the drawers-hook from the shank 3.

It will be seen that this combination suspender button and drawers hook may be 75 securely fastened in place without the aid of any tool whatever and that its construction is so simple as to require but a minimum cost in the manufacture thereof.

In use, the shank 3 is passed through the 80 garment 4, and the enlargement 5 is passed through the opening 8, whereupon the enlargement is rotated over the spring so as to be confined between the end thereof and the abutment, thus preventing accidental 85 separation. By depressing the spring and reversing the operation, the parts may be separated.

I desire it to be understood that I may make slight changes in the combination and 90 arrangement of parts without departing from the spirit of the invention, provided such changes come within the scope of the appended claim.

Having thus fully described my invention, 95 what I claim as new and desire to secure by Letters Patent is:—

A drawers hook including a plate having

a hook at its lower end, said plate provided with a transverse opening therein, a portion being struck up from said plate subjacent the opening to provide an abutment, a portion of the plate in proximity to the abutment being partially severed from the body to provide a spring, and a button having a shank with an elongated enlargement there-

on adapted to be passed through said opening and to be rotated over the spring, so as 10 to be held between the end of the spring and the abutment.

JOHN LOEFFLER.
